UNITED STATES PATENT OFFICE.

CARL O. LUNDHOLM, OF MOIENE, MONTANA.

MEASURING DEVICE FOR CONTAINERS.

Application filed February 3, 1927. Serial No. 165,745.

This invention has for one of its objects to provide a container for granular or powdered materials which shall embody novel, simple and inexpensive means through the medium of which its contents may be discharged in measured quantities, the means being adapted to be adjusted to permit the entire contents of the container to be discharged in one operation if desired.

With the foregoing and other objects in view, the nature of which will become apparent as the description proceeds, the invention consists of the construction, combination and arrangement of parts hereinafter fully described and claimed, and illustrated in the accompanying drawing, wherein:

Figure 1 is a sectional view taken on a plane extending vertically and centrally through a container embodying the invention.

Figure 2 is a horizontal sectional view taken on the plane indicated by the line 2—2 of Figure 1.

Figure 3 is a view similar to Figure 1 with the container in inverted or discharging position.

Figure 4 is a view similar to Figure 1 illustrating a slightly modified form of the invention.

Figure 5 is a sectional view taken on the plane indicated by the line 5—5 of Figure 4.

Figures 6 and 7 are similar views illustrating further modified forms of the invention, and

Figure 8 is a top plan view of a fragmentary portion of the container as shown in Figures 1 to 3 with the valve plate removed, illustrating the formation of the discharge opening of the container, and

Figure 9 is an elevational view of a fragmentary portion of the valve plate as shown in Figures 1 to 3 illustrating the manner in which it is graduated.

Referring in detail to the drawing, in the several views of which like reference characters denote like parts, 1 designates the side, 2 the top and 3 the bottom of the container which may be made of sheet metal, cardboard, fiber or any other suitable material or materials and which may be cylindrical, as shown, or of any other desired configuration. The top 2 is provided adjacent the side 1 with a segmental opening 4

through which the contents of the container 55 is discharged in measured or unmeasured quantities.

A flat partition 5 is arranged vertically within the container, and extends from the top 2 to the bottom 3 with its upper edge in alinement with the straight wall of the discharge opening 4 and with its side edges in contact with the inner surface of the side 1. The partition 5, which may be made of any suitable material and is secured in place in any suitable manner, separates the container into a comparatively large supply compartment 6 and a comparatively small measuring and dispensing compartment 7. The partition 5 is provided adjacent its upper end with an opening 8 and at its lower end with an opening 9.

A flat valve plate 10 is slidably mounted in the measuring and dispensing compartment 7 by having its side edges positioned in the corners of said compartment. The valve plate 10, which in length is equal to the depth of the container and the width of which is slightly less than the corresponding dimension of the partition 5, is held in full abutting contact with the partition by reason of the engagement of its side edges in the corners of the measuring and dispensing compartment 7. The upper end of the valve plate 10 is provided with an extension 11 which constitutes a closure for the discharge opening 4 and a finger piece by means of which said plate may be raised into opened position or lowered into closed position. When in closed position, the valve plate 10 cuts off all communication between the supply compartment 6 and the measuring and dispensing compartment 7, and when in opened position, it uncovers the opening 9 to permit a quantity of the contents of the supply compartment to flow into the measuring and dispensing compartment. When the valve plate 10 is in closed position, the angular end 11 thereof is in position to close the discharge opening 4. If desired the partition and valve plate may be of arcuate formation as shown at 5^b and 10^b in Figure 6 or of angular formation as shown at 5^c and 10^c in Figure 7. Furthermore, the partition may be made shorter than the depth of the container and arranged therein with its ends spaced from the top 2 and bottom 3 in order to provide the openings 8 and 9.

100
105

The container may be used for the purpose of distributing predetermined quantities of poisoned grain or meal for gophers, mice and the like. It may also be used for the purpose of dispensing predetermined quantities of ground coffee, sugar, salt, and the like. When it is desired to remove a quantity of the contents of the container, the valve plate 10 is first raised to uncover 10 more or less of the opening 9, with the result that the quantity of the contents will flow through said opening from the supply compartment 6 into the measuring and dispensing compartment 7. The container is 15 then inverted to permit the measured quantity of the contents to flow out through the discharge opening 4. The extent to which the opening 9 is uncovered determines the amount of the contents of the container that 20 will flow out of the discharge opening 4 when the container is inverted, and to permit the amount to be accurately gaged the valve plate 10 is graduated as shown at 12.

In practice, the supply compartment 6 is 25 not completely filled, in order to prevent the contents from flowing from said compartment into the measuring and dispensing compartment 7 by way of the opening 9 when the container is inverted to discharge 30 the measured quantity therefrom. If it is desired to remove the entire contents of the container, or if it is desired to remove a greater amount than can be measured and removed in one operation, the valve plate 10 is withdrawn from the measuring and dispensing compartment 7, and thereafter the container is inverted to permit its entire contents or as much as desired to flow out through the openings 4 and 8.

40 The modified form of the invention shown in Figure 4, differs but slightly from the invention shown in Figures 1-3. In this form of the invention, the measuring and dispensing compartment 7^a is located outside of the container, and is provided by securing the edges of an arcuate strip 5^a to the side 1^a. The lower end of the measuring and dispensing compartment 7^a is closed, and the upper end thereof is open to provide a discharge opening. In this form of 45 the invention, the entire container constitutes the supply compartment, and communication between the lower ends of the supply compartment and the measuring and dispensing compartment 7^a is established by means of an opening 9^a formed in the side 1^a. Communication between the upper ends of the compartments is established by an opening 8^a formed in the side 1^a. The valve 50 plate 10^a is arcuate, its side edges are positioned in the corners of the measuring and dispensing compartment 7^a, and it contacts with that portion of the side 1^a that constitutes one wall of this compartment. The 55 valve plate 10^a is provided at its upper end

with a combined closure and finger piece, and is also graduated in a similar manner as valve 10.

It should be understood that the drawing is merely illustrative and does not pretend 70 to give exact proportions. Furthermore, the said drawing is illustrative of a preferred construction, it being my expectation that various changes and modifications may be made without departing from the 75 spirit and scope of my invention.

What is claimed is:—

1. A device of the character set forth, comprising a container, a partition separating the container into a supply compartment 80 and a measuring and dispensing compartment, the latter being open at its upper end, the partition being provided at its lower end with an opening, a valve plate slidably mounted in the measuring and dispensing 85 compartment and contacting with said partition for covering and uncovering the opening therein, and a closure for the upper end of the measuring and dispensing compartment and carried by the valve plate. 90

2. A device of the character set forth, comprising a container having a supply compartment and a measuring and dispensing compartment, the measuring and dispensing compartment having a discharge opening, 95 the wall between the compartments being provided with upper and lower openings, and a valve plate slidably and removably mounted in the measuring and dispensing compartment and contacting with said wall 100 for covering and uncovering the openings therein.

3. A device of the character set forth, comprising a cylindrical container, a partition extending from the top to the bottom 105 of the container and having its side edges secured to the cylindrical wall of the container, the partition being provided adjacent its upper end with an opening and at its lower end with an opening, the partition 110 separating the container into a comparatively large supply compartment and a comparatively small measuring and dispensing compartment and the openings in the partition establishing communication between 115 the compartments, the top wall of the container being provided with a discharge opening for the measuring and dispensing compartment, a valve plate slidably mounted in the measuring and dispensing compartment, the side edges of the valve plate being positioned in the corners of the measuring and dispensing compartment, and a closure for 120 said opening in the top wall of the container and carried by the upper end of the valve 125 plate.

4. A device of the character set forth, comprising a container having a supply compartment and a measuring and dispensing compartment, said compartments commun- 130

cating at their upper and lower ends, and a valve plate slidably mounted in the measuring and dispensing compartment for establishing and cutting off communication between said compartment and the supply compartment.

5. A device of the character set forth, comprising a container having a supply compartment and a measuring and dispensing compartment communicating at the lower

end of the container, the container being provided in its top wall with a discharge opening for the measuring and dispensing compartment, and a valve plate slidably mounted in the measuring and dispensing compartment for cutting off and establishing communication between this compartment and the supply compartment.

In testimony whereof I affix my signature.
CARL O. LUNDHOLM.
